United States Patent

Des. 236,682
Patented Sept. 9, 1975

236,682

ESCUTCHEON

La Verne E. Clayton, Rockford, Ill., assignor to
Amerock Corporation, Rockford, Ill.

Filed Dec. 26, 1973, Ser. No. 427,726

Term of patent 14 years

Int. Cl. D8—09

U.S. Cl. D8—179

FIG. 1 is a front view of an escutcheon incorporating my new design.

FIG. 2 is a side view of the escutcheon as seen from the right in FIG. 1.

FIG. 3 is a bottom view of the escutcheon.

FIG. 4 is an enlarged sectional view taken along the line 4—4 in FIG. 1.

I claim:

The ornamental design for an escutcheon, as shown.
